UNITED STATES PATENT OFFICE.

GEORG SPIESS, OF LEIPZIG-REUDNITZ, GERMANY, ASSIGNOR, BY MESNE ASSIGNMENTS, TO THE FIRM OF CANADIAN AMERICAN MACHINERY COMPANY LIMITED, OF LONDON, ENGLAND.

SHEET-FEEDING MECHANISM FOR PAPER.

1,118,823.

Specification of Letters Patent.

Patented Nov. 24, 1914.

Application filed March 21, 1914. Serial No. 826,450.

To all whom it may concern:

Be it known that I, GEORG SPIESS, a subject of the Emperor of Germany, residing in Leipzig-Reudnitz, Germany, have invented certain new and useful Improvements in Sheet-Feeding Mechanism for Paper and the like, of which the following is a specification.

In the usual sheet feeding mechanism, that is to say, in the machines in which individual paper sheets are feathered out and separated and fed forward from a pile of sheets by combing wheels a particular arrangement is as a rule provided for the purpose of throwing the combing wheels out of action while another device is usually arranged for actuating the roll by which the pile of paper sheets is advanced to the combing wheels. Both these movements are effected in a certain relation one to the other and the throw-out mechanism for the combing wheels must be released at the instant in which a sheet in advancing with its forward edge between the transfer rollers is caused to actuate what is generally called a detector or trip lever. The slightest force of the paper edge even of a very thin sheet must suffice to bring about the throw-out action. In such mechanical paper feeders the detector is generally arranged on a rocker arm which is pivoted at some convenient point and carries or operates a separate pawl employed to bring about the release of the throw-out mechanism. For instance, in some cases it has been proposed to use such a trip lever operated by the paper sheet and a pawl moved by this action into engagement with a rotary toothed driving member whereby the pawl is then actuated to release a throw-out mechanism for the combing wheels. It has, moreover, been suggested to employ in the place of a toothed rotary driving member a toothed rack which is arrested by a locking pawl when the trip lever is raised by the sheet and thereby is caused temporarily to suspend the reciprocal movement of a carriage provided with sheet feeding claws without raising the latter from the sheets. Further, in machines of this kind it has been proposed to transmit movement from the driving shaft to the pile feeding roller

while the sheet-feeding or combing wheels are out of action.

Now according to this invention the pawl which is actuated by the rocker arm when the detector is tripped up by the sheet is caused to engage with a toothed rack which is yieldingly arranged on a moving member or rod so as to be capable of moving relatively thereto at the instant at which it engages with the locking pawl. This displacement of the rack moves the locking pawl which thereby releases the throw-out mechanism for the combing wheels. The locking pawl by entering the toothed rack arrests the forward movement imparted to the rack by its carrier or moving member, and as the latter continues its movement the rack is caused to be moved relatively thereto until an abutment arranged on the rod abuts against the rack, thereby limiting the extent of the rack movement on the rod and at the same time arresting the forward movement of the latter.

The moving member or rack carrier is actuated from a crank disk or the like whereby at certain periods it is moved only in one or rearward direction derived from which is also the movement of the sheet supply roller which advances the paper pile, whereas the opposite or forward movement of the rack carrier is due to the agency of a traction spring and is limited by the engagement of the rack with the abutment as above referred to, to an extent which pre-determines the subsequent backward throw of the rack carrier and consequently the extent of rotation of the sheet supply roller, so that the feed movement of the paper pile is brought into a definite relation to the feed and to the throw-out movement of the combing wheels, as will hereinafter be more fully explained.

The invention is illustrated by way of example in the accompanying drawings, in which—

Fig. 1 shows diagrammatically a sheet feeding mechanism of this kind in its normal or sheet feeding position, and Fig. 2 shows the same mechanism in the position in which the combing wheels have been raised from the feed table and the rack has been displaced relatively to its carrier.

In the construction shown, each combing wheel a is secured in a known manner to a rocking lever b . This lever is capable of being raised or lowered by means of a bell crank lever c . The forward end d of the lever c is supported in a known manner upon a sliding bolt f tending under the action of a spring g constantly to rise to its highest position in which the combing wheel a is held in a raised position, that is to say, is 5 inoperative as regards the feed movement of the paper sheets. Against the tendency of the spring g the bolt f is held wedged between two pins h and i which serve as 10 brake members. These pins are arranged one at each side of the bolt f on a link lever k which has its fulcrum at l and by means of a spring m is held in its highest position, in which the pins h and i hold the lever k 15 in its lowest or locked position. This lever k is operated by a double-armed lever n which is connected to lever k by a link o . The free end p of the lever n is by preference provided with a roller and extends into 20 the path of the known locking pawl q resting on the arm r which carries the detector s . When the arm r is rocked by the tripping of the detector s due to its contact with a sheet of paper, the pawl q descends 25 into the path of the teeth of the rack 6 and by engaging therewith is forcibly raised thus raising the lever n and thereby drawing down the lever k by the movement of which the braking action of the pins h and 30 i on the bolt f is released and the latter in being pulled up by its spring g causes the combing wheels a to be raised from the sheets. The pawl q is loosely rotatable on the axis to which the detector carrier r is 35 secured. The resetting of the lever k is effected in a known manner, for instance, by a driven cam y' carrying a projection y'' which at certain periods engages with a pin or other abutment y^3 suitably arranged on 40 the bolt f drawing the latter down and enabling the spring m to pull the lever k up into locking position, when the combing wheels are again lowered to act on the 45 paper sheets.

The rack 6 is arranged on a moving rod or rack carrier 5 so that it is capable of rising thereon and to this end in the particular example shown it is connected to the rod 5 by means of links 7 and 8 and by 50 means of a spring 9 which tends to draw the rack on to the rod. The rod 5 , moreover, carries an adjustable stop 10 adapted to limit the rising movement of the rack 6 . The rod 5 derives its movement 55 from a crank disk y through the agency of a connecting rod z coöoperating with a rocker 1 , as will be presently explained. t is the roller for advancing the paper pile u and this roller is rotated in a known manner 60 by a ratchet device comprising a ratchet 65

wheel v actuated by a pawl w which is pivoted to an oscillating arm x and by means of a toothed gearing (not shown) causes the roller t to be rotated.

The movement of the oscillating arm x 70 is likewise derived from the crank disk y by means of the connecting rod z which periodically transmits driving movement to the rocker 1 . To this end the rocker 1 carries a pin 2 guided in a slot 3 in the free end 75 of the connecting rod z and its lower end is attached to a traction spring 4 having its other end secured to a fixed frame portion and tending constantly to draw the rocker 1 , that is to say, the pin 2 into operative connection 80 with the slot 3 , and to pull the rod or rack carrier 5 in the (forward) direction indicated by the arrow A . The lower end of the rocker 1 is also connected by a pin and slot arrangement to the rod 5 , whereby (rearward) movement is periodically imparted to the latter in the direction of the arrow B and the extreme end of the rod 5 is connected in a similar manner to the end of the oscillating arm x for transmitting this movement to the ratchet gear of the pile feeding roller t .

Now when a sheet is fed forward by the combing wheel a the crank pin y rotating in the direction of the arrow C , and its forward edge trips the detector s the locking pawl q descends as already explained into engagement with the rack 6 which under the action of the spring 4 is moved forward with the rod 5 , and thereby arrests the forward movement of the rack. As, however, the rod 5 continues its forward movement under the influence of the spring 4 , with the pin 2 95 following the corresponding movement of the connecting rod z , the rack 6 in engagement with the pawl q is caused to rise on the rod 5 as shown in Fig. 2. In this rising movement the rack 6 raises the pawl q which in its turn raises the end p of the lever n whereby the brake lever k is drawn down in opposition to the action of its spring m . The locking bolt f is thus freed and flies up under the action of its powerful spring g , in which movement it raises the bell crank lever c to the position shown in dotted lines 105 in Fig. 1 and thereby throws the combing wheel a out of action.

As already stated, the rising movement of the rack 6 is limited by the abutment 110 arranged on the rod 5 , and as soon as this 120 abutment strikes the rack in the continued forward movement of the rod 5 , above referred to, the pawl q is caused also to arrest the further movement of the rod 5 and consequently that of the rocker 1 . This rocker 125 therefore now remains stationary, with the slot 3 gliding freely on the stationary pin 2 during the further forward rotation of the crank y and also during a certain period of the backward rotation thereof. To this end, 130

the slot 3 in the connecting rod 2 is so calculated that the latter, only in its return movement in the direction of the arrow D and when in this movement the forward end of 5 the slot 3 again engages the pin 2, is caused to operate the rocker 1 and accordingly the rod 5 in the direction of the arrow B, thus through the agency of the lever α rotating the supply roller t and advancing the pile, 10 the cam y' in the example shown being of such dimension and so arranged with regard to the crank y as to hold the combing wheel in its raised position until the feed movement of the supply roller has been completed. 15 It will be seen that this throw of the lever α and therefore the extent of the feed of the paper pile u is predetermined by the length of the movement to which the pin 2 has been moved forward by the rocker 20 1 under the action of the traction spring 4, or in other words, by the extent of forward movement of the rod 5, depending on the engagement of the rack 6 with the locking pawl g and the adjustable abutment 10 on its carrier. Thus the rack 6 controls by its movement both the releasing mechanism of the throw-out device for the combing wheels and the extent of the return or pile 25 feeding movement of the rack carrier or moving rod 5, or the throw of the ratchet device of the sheet supply roller, as will be readily understood.

What I claim and desire to secure by Letters Patent is:—

35 1. Sheet feeding mechanism for paper and the like comprising the combing wheels, throw-out mechanism therefor, locking means for the said mechanism, a carrier, a rack yieldingly arranged thereon, a pawl operating with the rack and a detector for the fed sheets for moving the pawl into engagement with the rack to operate the locking means by the displacement of the rack from the carrier.

45 2. Sheet feeding mechanism for paper and the like comprising combing wheels, throw-out mechanism therefor, locking means for the said mechanism, a pawl engaging with said means to release the same, a detector engaging with the pawl, a movable carrier, a rack adapted to move relatively to the carrier and to engage with the pawl links connecting the rack with the carrier and a spring for holding the rack down on the 55 carrier.

3. Sheet feeding mechanism comprising the combing wheels, throw-out mechanism therefor, locking means for said mechanism, a detector, a pawl operated by the detector and engaging with the locking means, a carrier, a rack yieldingly carried thereby and engaging with the pawl and an adjustable

abutment on the carrier engaging the rack to limit the movement of the same and to arrest the movement of the carrier.

65

4. Sheet feeding mechanism comprising the combing wheels, throw-out mechanism, a detector, a pawl operated thereby and engaging the locking means, operating mechanism for the wheels, a moving member connected to said operating mechanism, a spring for moving said member in one direction, a rack yieldingly arranged on the said member and adapted to engage the pawl, an adjustable abutment on the member adapted 70 to engage with the rack to limit the movement of the member by the spring.

75

5. Sheet feeding mechanism comprising the combing wheels, throw-out mechanism therefor, locking means for said mechanism, a detector, a pawl operated thereby and engaging the locking means, operating mechanism for the wheels, a moving member connected to said operating mechanism, a spring for moving said member in one direction, a 80 rack yieldingly arranged on the said member and adapted to engage the pawl, an adjustable abutment on the member adapted to engage with the rack to limit the movement of the member by the spring and 85 means for actuating the said member in the opposite direction to an extent predetermined by its preceding movement for controlling the feed of the combing rollers.

90

6. Sheet feeding mechanism comprising 95 combing wheels, throw-out mechanism therefor, a clamping device for locking and releasing said mechanism, a moving member, a rack movably carried thereon, a pawl, a detector for moving the pawl into engagement with the rack, and a member operated by the pawl through the agency of the rack for actuating the clamping device.

100

7. In sheet feeding mechanism for paper and the like, the combination of a carrier, a 105 rack movably arranged on the carrier, a pawl adapted to engage with the said rack, an adjustable stop on the said carrier and adapted to engage with the said rack, a throw-out mechanism for the combing 110 wheels, a device for releasing and locking the said releasing mechanism controlled by the engagement of the said rack with the said pawl and operating mechanism for the sheet supply roller controlled by the engagement of the said rack with the said pawl, 115 all substantially as shown for the purpose specified.

115

In testimony whereof I have affixed my signature in presence of two witnesses.

GEORG SPIESS.
